UNITED STATES PATENT OFFICE.

FREDERICK MACMONNIES, OF PARIS, FRANCE, ASSIGNOR TO THE NIAGARA FALLS POWER COMPANY, OF NEW YORK, N. Y.

DESIGN FOR A SEAL.

SPECIFICATION forming part of Design No. 22,658, dated August 1, 1893.

Application filed May 10, 1893. Serial No. 473,734. Term of patent 14 years.

To all whom it may concern:

Be it known that I, FREDERICK MACMONNIES, a citizen of the United States of America, residing at 16 Impasse du Maine, in the city of Paris, Republic of France, have invented a new and original Design for Seals, of which the following is a specification.

In the accompanying drawing, in which similar letters refer to similar parts, the figure 10 represents a face view of my design.

This invention relates to a new and original design for seals and similar articles; and the leading features of which consist of a disk or circular surface in the center of which is represented an Indian chief, paddling down the Niagara rapids. The details of the Indian's dress and position are that he has a full head dress, with a quiver of arrows strung across his shoulders and he is standing in a canoe 15 with his left knee bent toward the bow; a border surrounds the figure which I have shown, composed of a circular ring of beads, as shown by the letters b, b, b.

The outer border of the design is composed of a string of conventional representations of the shell fossil frequently found in the Niagara limestone, known as *Delthyse Niagaren-sis*. Between this border and the circular ring of beads, b, b, b, is another border, d, d, composed of the fish known as "muskalonge," 25 the king fish of Niagara river. Each muskalonge is preceded by an arrow-head e, e, both arrow-heads and muskalonge forming a circle between the beads and shells—the whole forming my design.

What I claim, and desire to secure by Letters Patent, is—

The design for seals as herein shown and described, consisting essentially of an Indian, paddling a canoe, surrounded by an ornamental border substantially as described.

FREDERICK MACMONNIES.
